UNITED STATES PATENT OFFICE.

STANLY J. YELLEN, OF GREAT NECK, NEW YORK.

MINER'S LAMP.

1,136,303.

Specification of Letters Patent. Patented Apr. 20, 1915.

Application filed October 1, 1914. Serial No. 864,461.

To all whom it may concern:

Be it known that I, STANLY J. YELLEN, citizen of Russia, residing at Great Neck, in the county of Nassau, Long Island, and State of New York, have invented certain new and useful Improvements in Miners' Lamps, of which the following is a specification.

This invention relates to miners' lamps and has as its primary object to provide a lamp which may be readily attached to a miner's cap to be held securely in position thereon, which may be detached from the cap with equal facility, and which will be so constructed as to conform to the contour of the crown of the cap and will thus be thoroughly comfortable in use.

The invention has as a further object to provide a miner's lamp wherein a lamp chimney will be employed so that the lamp will give out an even and steady light and wherein the said chimney will be thoroughly protected so as not to become broken.

A further object of the invention in this connection is to provide a cage or protector for the lamp chimney so constructed, that when applied in use, the said protector will coact with the resilient fingers of the lamp burner in holding the lamp chimney in position upon the burner, and wherein the said protector will be so arranged as to prevent objects, such as falling pieces of coal from gaining entrance into the chimney or from striking against the chimney. And the invention has a still further object to generally improve the construction and increase the efficiency of devices of the above described character.

With these and other objects in view my invention will be more fully described, illustrated in the accompanying drawings, and then specifically pointed out in the claims which are attached to and form a part of this application.

In the accompanying drawings:—Figure 1 is a perspective view of my improved lamp applied to a cap, the cap being conventionally illustrated, Fig. 2 is a perspective view of the cap showing the attaching plate secured thereto, Fig. 3 is a perspective view showing the lamp reservoir detached, with the burner removed therefrom and particularly illustrating the arrangement of hooks

carried by the reservoir which are disposed to engage the attaching plate carried by the cap, as well as showing the arrangement of straps secured to the reservoir and disposed to engage around the cap, Fig. 4 is a fragmentary transverse sectional view taken through the reservoir, the burner not being shown, Fig. 5 is a detail perspective view of the cage for the chimney, the cage being shown removed, and Fig. 6 is a vertical sectional view showing the cage applied.

Corresponding and like parts are referred to in the following description and indicated in all the views of the drawings by the same reference characters.

For convenience, I have illustrated in the accompanying drawings my improved miners' lamp in connection with a cap 10, of usual construction, the lamp being shown in Fig. 1 of the drawings in operative position upon the cap. Secured upon the forward side of the crown of the cap is an attaching plate 11 which is preferably formed of suitable sheet metal and which, at the corners thereof, is provided with a plurality of apertures through which stitching is passed in attaching the plate to the cap. Arranged upon the forward side of the plate 11, are a plurality of loops 12, said loops being arranged in pairs disposed adjacent opposite ends of the plate and the loops of each pair being arranged in alignment transversely of the plate.

Arranged for detachable connection with the attaching plate 11 is the reservoir 13 of the lamp proper. The reservoir 13 may be formed of any suitable material and is preferably oblong, as illustrated in the drawings, the said reservoir being longitudinally curved to conform to the contour of the crown of the cap as is also the attaching plate 11, so that the reservoir will fit snugly against the attaching plate and against the crown of the cap, to thus provide a construction thoroughly comfortable to the user. Disposed upon the rear concave side of the reservoir 13, are downwardly projecting longitudinally spaced attaching members or hooks 14. Each of the hooks 14 is preferably formed from a length of suitable resilient wire which is secured adjacent one end, to the reservoir 13 by a suitable strip 15, the length of wire being

thence bent upon itself to extend in spaced relation upon one side of the adjacent face of the reservoir, it being observed that the strip 15 is looped over the adjacent terminals of the hooks to thus maintain the hooks seated firmly against the reservoir, the said strip 15 being secured to the reservoir in any suitable manner. The hooks 14 are disposed to engage within the loops 12 carried by the attaching plate 11 and as will be readily understood, the reservoir may, in this manner, be readily mounted upon the cap 10 and may be disconnected therefrom with equal facility, while the hooks 14 are so arranged upon the reservoir as to hold the reservoir firmly in position when attached to the cap. However, in order that the reservoir may be positively prevented from becoming detached from the cap, even under extreme conditions, coacting flexible members or straps 16 are provided, the said straps being each secured at one extremity to suitable loops 17 carried by the strip 15, one of said straps at its opposite extremity being provided with a suitable buckle disposed to engage the free extremity of the opposite strap, as shown in Fig. 1 of the drawings. The straps 16 are disposed to engage around the crown of the cap and may be adjusted to comfortably embrace the head of the wearer. By this arrangement, it will be seen that the straps 16 will coact with the hooks 14 in holding the lamp securely upon the cap.

Upon its upper side and medially thereof, the reservoir 13 is provided with a screw-threaded opening in which is disposed to engage a tubular socket 17, the said socket extending vertically within the reservoir and terminating at its inner extremity adjacent the bottom wall of said reservoir. At its outer extremity, the socket 17 is enlarged and is internally screw threaded to receive the base of the burner 18. The socket 17 is thus detachably connected with the reservoir 13 while the burner 18 is also detachably engaged with the socket, this construction making it readily possible to detach the several parts of the device in order that they may be kept in proper working condition. The reservoir 13 is, of course, disposed to receive a suitable illuminating oil and in providing the socket 17, the said oil will be prevented from spilling or from flowing up to choke the burner when the lamp is held in different angular positions in the practical use of the device.

The burner 18 may be of any conventional construction and the gallery thereof is provided with the usual resilient fingers 19 which are disposed to embrace and resiliently engage a chimney 20. In order to protect the chimney from falling pieces of coal or other objects and to prevent foreign matter from gaining entrance within

the chimney, I provide a cage which, in Fig. 1 of the drawings, I have indicated as a whole at 21, the said cage being more specifically shown in detail in Figs. 5 and 6 of the drawings. More particularly, the cage 21 includes the upper and lower annular members 22 and 23 which are each formed from a length of suitable resilient wire, the member 23 being in the form of a split ring and being provided at its extremities, with coacting hooks 24 which are disposed to be detachably engaged. Connecting the members 22 and 23 are a plurality of vertically extending members 25 and 26 which are also preferably formed from suitable resilient wire. At their lower extremities, the members 25 and 26 are looped about the ring 23, as shown at 27, and the upper extremities of the members 25 terminate at the ring 23 and are looped about the said ring as shown at 28. The members 26 adjacent their upper extremities are also looped around the ring 23 as shown at 29 and are thence extended vertically to support a suitable metallic disk 30, the said disk being provided with suitable apertures disposed to receive the upper terminals of the said members 26, which terminals are bent about the periphery of the disk as shown at 31.

Surrounding the upper portion of the cage and arranged upon one side of and above the member 22 is a collar 32 which may be formed of any suitable material and which is supported by a plurality of vertically extending members 33, the members 33 being also preferably formed from suitable wire and being looped about the ring 23 at their lower extremities and passed through suitable apertures formed in the collar 32 and looped about the edges of the said collar at their upper extremities. The collar 32 will thus be held in position by the members 33 and as shown in Fig. 1 of the drawings, the said collar is notched as at 34 to receive the upper extremities of the members 26 which fit within the said notches and thus hold the collar 32 from possible turning movement about a vertical axis.

The cage thus formed is disposed to detachably fit over the chimney 20 as shown in Figs. 1 and 6 of the drawings with the member 23 fitting around and clamped against the resilient-fingers 19 of the burner 18. The member 23 is preferably of such diameter that when the hooks 24 thereof are engaged as shown in Fig. 5 of the drawings, the said member will act to force the resilient fingers inwardly against the chimney 20 to thus hold the chimney firmly in position upon the burner, the said member 23 in this manner coacting with the resilient fingers 19 in maintaining the chimney in place. It will be observed that when the cage is thus mounted upon the chimney, that the disk

30 will be supported in spaced relation above the upper extremity of the chimney in such position as to provide a protecting plate disposed to prevent foreign matter 5 from gaining entrance into the chimney and to also prevent objects from falling either into or against the upper extremity of the chimney. As best shown in Fig. 6 of the drawings, the collar 32 is of a diameter 10 greater than the diameter of the chimney at its widest part and is thus disposed to prevent falling objects from striking the chimney, while the members 25, 26, and 33 will extend vertically of the chimney and are 15 thus disposed to prevent objects from striking the sides of the chimney.

Attention is now called to the fact that the collar or deflecting plate 32 is substantially concavo-convex to incline outwardly 20 and downwardly away from the chimney. Consequently, objects striking the said collar will be directed away from the chimney by the inclined faces presented by the collar. In a device of this character, this is obviously 25 a feature of advantage since particles of coal falling from the roof of a mine, in the practical use of the device, in striking the collar or deflecting plate 32, will be prevented from coming in contact with the 30 chimney 20 to cause injury thereto.

It will thus be seen that I provide a very simple and efficient construction for the purpose set forth, wherein a lamp is provided which employs a chimney to the end 35 that an even and steady light may be had, and wherein the said chimney will be effectually protected in use. It will further be seen that by the construction which I provide, the means employed for protecting 40 the chimney will also coact to hold the chimney firmly in position upon the burner. Further, it will be seen that I provide a lamp which may be readily attached to or detached from a miner's cap and wherein 45 the lamp will be held firmly in position upon the cap in use.

Having thus described my invention what I claim and desire to secure by Letters Patent is:—

1. A miner's lamp including a reservoir 50 adapted for attachment with a head covering and provided with a concave face disposed to confront the head covering, hooks arranged in longitudinal spaced relation upon the concave face of the reservoir, a strip securing said hooks to the reservoir, loops carried by said strip, coacting flexible elements engaging said loops and disposed to embrace the head covering, an attaching plate carried by the head covering, and longitudinally 55 spaced and transversely alined loops carried by said attaching plate and disposed for engagement with said hooks.

2. A miner's lamp including a reservoir, a strip secured to one side of the reservoir, 65 loops carried by said strip, the ends of the strip being passed through the loops, a hook connected at one terminal to the reservoir by said strip, an attaching plate adapted to coact with said hook, and coacting flexible 70 elements connected to said loops, the said attaching plate being adapted for connection to a head covering and said flexible elements being adapted to extend around the 75 said covering.

3. A miner's lamp including a reservoir, a strip secured to one side of the reservoir, loops freely mounted on said strip, coacting flexible elements connected to said loops, spaced hooks terminally connected to the 80 reservoir by said strip, and an attaching plate adapted to coact with said hooks, said plate being adapted for connection to a head covering and the flexible elements being adapted to extend around the head covering. 85

In testimony whereof I affix my signature in presence of two witnesses.
